UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-PLATE.

SPECIFICATION forming part of Design No. 27,990, dated December 7, 1897.

Application filed October 2, 1897. Serial No. 653,864. Term of patent 14 years.

To all whom it may concern:

Be it known that I, FRANK L. WRIGHT, a citizen of the United States, residing at Chicago, in the county of Cook and State of Illinois, have invented a certain new and original Design for a Prism-Plate, of which the following is a specification.

My invention relates to designs for prism-plates, and is illustrated in the accompanying drawings.

Figure 1 is a view of a prism-plate. Fig. 2 is a section therethrough.

A is a prism-plate having prisms on one

side and provided with the circular portion B. The plate consists of a substantially flat 15 body.

The essential features of my design are found in a substantially flat prism-plate with the circular part B.

I claim—

A design for a prism-plate substantially as shown and described.

FRANK L. WRIGHT.
